FIG. 10

UNITED STATES PATENT OFFICE

JOHN C. LEARY, OF SAN FRANCISCO, CALIFORNIA

PISTON MECHANISM FOR INTERNAL-COMBUSTION ENGINES

Application filed July 24, 1924. Serial No. 727,985.

My invention relates to means for quickly and easily removing the piston-head from an internal combustion engine and for varying the compression space in said internal 5 combustion engine.

An object of the invention is to provide a piston-head that can be readily detached from the wrist pin, and withdrawn through what is generally called the head end of an 10 internal combustion engine, without disturbing the crank-case or crank-pin bearings. Another object is to provide a means by which the compression space can be readily varied.

15 The invention possesses other objects and features of advantage, some of which with the foregoing will be set forth in the following description of the preferred form of my invention, which is illustrated in the drawings accompanying and forming part of the 20 specification. It is to be understood that I do not limit myself to the showing made by the said drawings and description, as I may adopt variations from the preferred form 25 within the scope of my invention, as set forth in the claim.

Referring to the drawings.

Fig. 1 is a front elevation of an ordinary 30 internal combustion engine with shell broken to show a sectional view of a piston equipped with my preferred device.

Fig. 2 is a sectional view of what will hereafter be referred to as the outer shell.

35 Fig. 3 is a plan view of the head of this shell.

Fig. 4 is a sectional side view of what is 40 called the inner shell (or spider) showing wrist pin bearings, bosses for bolts, and connecting rod suspended.

Fig. 5 is a plan view of this inner shell.

Fig. 6 is the outer shell of a piston with a 45 straight bore referred to in specifications.

Fig. 7 is a sectional view of inner shell or 50 spider for Fig. 6.

Fig. 8 is a device to keep bolts from turning when once screwed up.

Fig. 9 is an alternative device for keeping 55 bolts from turning.

50 Figure 10 is a perspective view of a distance

piece for use in the embodiment of Figures 6 and 7.

Probably, one of the most annoying troubles of the ordinary internal combustion engine, is a leaky piston or pistons. Due to the general construction, these pistons are very hard and disagreeable to get at. The crank case with all its bolts has to be removed, the connecting rod disconnected, and the piston pulled down through the cylinder, or up 60 through the head; then when the trouble is remedied, all these parts and bolts have to be replaced, new gaskets probably installed and all bolts tightened up well.

All this time the mechanic doing the work 65 is in a very disagreeable and awkward position, whether the machine is on skids, or over a pit, or he lying on his back on the ground.

It will be readily seen by glancing at the 70 drawings that all this disagreeable work is done away with. The crank case would only have to be disturbed in overhauling the crank pin and main bearings, which is rare, as these parts practically run in oil, and have little wear, and then again the thrust in this type 75 of engine is always down, with the exception of the suction stroke, and that due to the weight of the piston and rod is practically nil. The saving in time and expense in removing pistons should be readily discerned. 80

In the designing of internal combustion engines, the designer generally lays out the compression space to suit as close as possible 85 all localities, but it frequently happens that a motor that gives excellent results at a low altitude will not act the same in high altitudes. This is due to the difference in atmospheric pressure as the air will not flow in as fast as in the lower altitudes. By screwing the outer shell up or down as in the 90 embodiment of Figures 1 to 5, or by using a distance piece as in Fig. 6 the proper density of mixture can be obtained.

My improvement is what might be 95 termed a piston within a piston, in that the piston proper is composed of two main parts, an outer shell, and another shell or spider that fits into the outer shell and is secured therein. The term spider alluded to, is to be understood as a method of light- 100

ening up the structure to the extent that the inner shell need not fit the outer shell but here and there, but still have sufficient bearing surface for strength and rigidity.

5 Referring again to the drawings.

No. 1 is a cylinder showing piston mounted for reciprocation. It will be observed that the outer shell No. 2 is drawn line to line where it meets inner shell No. 3 on top, showing that the piston is set for a maximum compression space. Bolts No. 4 are shown tightened up. It may be well to state here that the different figures are all drawn half size of an engine of this type, scale being 15 $\frac{1}{2}$ " to 1". Actual sizes of cylinder being $3\frac{3}{4}$ " bore and 4" stroke, connecting rod 7" center to center. It will be noticed that the piston rings in shell No. 2 are $\frac{1}{8}$ " lower than in Fig. 6 which would amount to $\frac{1}{4}$ " full size, and which is considered ample and which would allow plenty of bolt hold when head is raised up to lessen the compression space and still leave piston rings below top of cylinder.

20 25 Both outer shell No. 2 and inner shell No. 3 are turned to a good sliding fit at No. 5. Shell No. 2 has an internal thread cut into it at No. 6 and inner shell No. 3 an external thread at 6 with this thread longer and lower 30 in the shell to permit it being raised and all necessary threads be in service.

To examine rings. Take out bolts No. 4, screw outer shell out of threads and pull out.

To alter compression. Take out bolts No. 35 4, unscrew outer shell to the desired position and replace bolts No. 4. Piston should be on upper center when this is done. Two stray bolts entered in bolt holes of outer shell and a bar between them for a lever enables this to be done very easily.

40 Where pistons are supplied with the shells threaded at No. 6, two bolts preferably the two parallel with the wrist pin, are sufficient. This also applies to pistons where the connecting rods has a bolted on cap on the wrist pin end. In this case the two bosses, that are in way of the swinging of the cap are also left out.

45 50 Depressions No. 8 are preferably hexagon shaped and it is essential that the bolt heads therein be prevented from turning, and crystallizing from heat as much as possible. A nonburnable cement placed between the bolt head sides and the hexagon shaped depressions, should accomplish this purpose. I have designed metal protection and holding members 11 and 12 which are respectively disclosed in developed form in Figures 8 and 9; either of said members being arranged to 55 60 be engaged about a bolt head after the latter is in a depression 8.

The embodiment shown in Figures 6 and 7 can also be made with or without the variable compression features. Drawing (No. 65 6) shows the nonvariable in that the upper

piston rings are closer to the top. To be variable, the upper rings should be lower as in Fig. 1 and what is generally spoken of as a distance piece inserted between the bosses on shell No. 3 and where they meet shell No. 70 2. As here shown, the distance piece, or spacing member, 13 is in the form of an annular ring perforated to loosely receive the bolts 4. There being no threads on this type, shell No. 3 is turned all the way, excepting between where it may be spidered, to a nice sliding fit. As a precaution against accidents, all four bolts are used in this design.

75 Dotted circles No. 9 may not be used at all. They represent the position where rivets may be if it is desirous of using an old style piston shell. These shells are generally very thin, therefore they would have to be reinforced by riveting a piece onto them formed for that purpose.

I claim—

In a piston for a reciprocating engine, an exterior member defining the piston walls and piston head, an interior member arranged for threaded engagement with and within said exterior member whereby relative axial adjustment of said members in a plurality of predetermined relative positions may be effected upon relative rotation 95 of the members through rotative angles of less than 360 degrees, a wrist pin mounted in said interior member and a bolt operable from the head end of said piston and arranged to axially draw said members together to thereby lock them against axial and rotative displacement.

JOHN C. LEARY.
